CONDENSER

Henry E. Byer, Bernardsville, N. J.

Application June 28, 1945, Serial No. 601,573

8 Claims. (Cl. 261—19)

1

This invention relates to condensers of the variety having tail or drain pipes and is particularly concerned with improvements in said tail or drain pipes. It is especially useful in conjunction with direct contact steam condensers wherein the steam condensing chamber is cleared of all of the waste water together with such air and non-condensable gases as may be carried out with the water stream.

It has for one of its objects the remedying of a defect common therein which results from the currently employed method of sealing the open end of the barometric pipe directly in an open hot-well, against the surface of which atmospheric pressure acts.

The operational defect, shown by commercial experience, is that because of so submerging the barometric pipe, there is a "creep" in the vacuum carried in the condenser, due to atmospheric variation, resulting in a longer period of time to accomplish the processing being carried out, with an increase in heat required to effect it, and increased production cost.

The above mentioned "creep" occurs as the strong falling water current in the barometric drain leg acts to isothermally compress such air and non-condensable gases as may be cleared from the condenser head by the egress of the waste water therefrom. With the open end of the barometric pipe submerged in the hotwell as is currently practiced, the atmospheric pressure represents the terminal pressure in the above isothermal compression cycle, and the vacuum pressure in the condenser, the initial pressure. It will be apparent that with the terminal pressure constantly changing, there can be no stability to the compression cycle, which varies directly as does the terminal pressure acted against. The variation in the terminal pressure based on the U. S. Weather Bureau for the year 1944 in New York city was .9 pound per square inch absolute, i. e., the barometer ranging from 30.72 inches to 28.92 inches corresponding to an absolute pressure of 15.10 lbs. per sq. in. and 14.20 lbs. per sq. in., respectively. The light weight of the gases being compressed by the falling water stream is easily affected as regards their acceleration or retardation in the water stream by such a continuous change in the terminal pressure discharged against. As the atmospheric pressure increases, there are slightly less air and non-condensable gases removed with a resultant decrease in vacuum in the condenser. As the atmospheric pressure decreases there are slightly more air and non-

5 condensable gases removed, with a resultant increase in the vacuum in the condenser. While the gases are being carried along by the water stream a certain amount of the gas will "slip-back" into the condenser. Also any undulations or surges in the liquid seal hot well will accelerate or retard the flow of gas through the liquid to atmosphere.

10 It must be understood that such vacuum changes in the condenser are so gradual as to require highly sensitive instruments not ordinarily employed in commercial operation to continuously record.

I remedy the above defect by stabilizing the 15 above mentioned hydraulic compression cycle by simple and cheaply made means, said means consisting of closing off the varying atmospheric barometric pressure from the exit point of the barometric pipe and substituting for it an absolute pressure kept substantially constant between the atmospheric pressure and vacuum in the condenser by positive rarifying means. To 20 accomplish this I attach a closed chamber at the exit point of the barometric drain pipe into 25 which the contents of the barometric pipe discharge. The water is removed from the closed chamber against atmospheric pressure, while a gas collecting chamber is provided above the 30 water level in the chamber, with rarifying means to maintain a constant pressure in said gas collecting chamber between atmospheric and that maintained in the condenser, irrespective of atmospheric pressure.

35 The maintaining at the discharge point of the contents of the barometric leg pipe of the required constant absolute pressure is assured thereby, as well as a constant vertical height as regards the compressing liquid column flowing from the condenser head into said chamber, the 40 variation in the atmospheric barometric pressure being compensated for by the means provided for the removal of the water from the chamber.

45 A further common defect in prior art structure is remedied by this invention, wh'ch is the surging set up in the barometric leg pipe when starting up the condenser. The surging is directly the result of submerging the open end of the 50 barometric drain pipe in an open hot well, whereby a water column rises from the hot well upward as the vacuum is built up while simultaneously the waste water begins to flow downwardly from the top of the pipe. As the empty barometric pipe is filled with atmospheric air 55 as a result of being inoperative, non-condensable

gases are entrapped between the two water columns. When these two water columns and gases impact, a heavy vertical surge in the barometric drain pipe develops resulting from the effect of the entrapped air to escape through the pipe into the hot well and such a surge can momentarily (as proved in commercial operation) be so violent as to throw some of the injection water back into the steam inlet pipe with consequent loss of commercial product or damage to the apparatus being served.

The above defect is remedied by my invention through employment of a by-pass pipe with shut off valve therein located between the gas collecting chamber of my invention and the lower end of the barometric pipe. With the condenser shut down, the barometric pipe is filled with atmospheric air and by first opening the valve in said by-pass, the rarifying means provided to rarify the gas collecting chamber will simultaneously rarify the barometric pipe and condenser. The valve in the by-pass pipe is then closed and the injection water is started through the condenser. When the falling water current meets the rising water column, there will be substantially no atmospheric air present to cause any surging.

While my invention may be used in connection with drain pipes employed with barometric, semi-barometric, or low level types of condensers, one form which my invention may assume is exemplified in the following description and indicated on the following drawings, in which a barometric condenser is indicated.

In the drawings

Figure 1 is a vertical broken view, partially in section, of one form of the invention.

Figure 2 is a sectional view of the lower portion of the tail pipe, chamber, and hotwell of Figure 1.

Figure 3 is a sectional view taken along the line 3-3 of Figure 2.

Figure 4 is generally similar to Figure 1 with the exception that a modified form of chamber is shown.

Figure 5 is a vertical section of the lower portion of the tail pipe and chamber of Figure 4.

Figure 6 is a section taken along the lines 6-6 of Figure 5.

Condenser 10 (Figure 1) may be any type of direct contact condenser having a tail pipe 11 of the barometric variety. Hot well 12 has weir 13 to retain water 14 at a level 30 as indicated. The water or liquid spills over weir 13 and may flow through passage 15 to waste. Outlet 16 of tail pipe 11 is connected to flange 17 of enclosed chamber 18. Chamber 18 has a central drain pipe 19 creating a catch basin or receptacle 25 therein, the upper edge 20 of said pipe being located at a height discussed hereafter. The upper portion or gas collecting space 21 of chamber 18 has an air removal means 22 connected to outlet flange 23, said air removal means being of any suitable type, a steam jet vacuum pump being illustrated. Steam jet air pump 22 may discharge to the atmosphere through exhaust opening 28. Water 14 in the hot well will seal the waste water outlet 24 of chamber 18.

Air and non-condensable gases carried into closed chamber 18 by the propelling liquid stream discharging through barometric pipe 11 will be evacuated from space 21 by steam jet air pump 22, the bending in path of the gases serving to facilitate their removal from the liquid. It is to be noted that there is a change in path from the tail pipe upwardly into the chamber and a second change as water flows over edge 20 downwardly.

After the condenser is started, water will flow down tail pipe 11 and will overflow the top of tube 20 into the hot well through waste water outlet 24.

Steam jet air pump 22 maintains a substantially constant absolute pressure in chamber 21 which is between atmospheric pressure and the absolute pressure maintained in the condenser, as will be explained hereafter. Vacuum relief valve 26 of the inward opening spring resisting type is provided so as to assist the pump in maintaining the absolute pressure, or rarefaction relative to atmosphere, constant within space 21, as the air and non-condensables delivered into chamber 21 will vary during the operating period of the condenser. As is well known, a steam jet air pump is not readily regulatable so the vacuum relief valve can be used in conjunction therewith to assist in maintaining the desired substantially constant pressure in chamber space 21. Other devices may be used to maintain a predetermined pressure therein or a regulatable vacuum pump employed.

By-pass valve 27 is provided in connection 28 so as to facilitate starting of the condensing system to prevent undesirable surges. When the condenser is to be started, valve 27 is opened and steam jet pump 22 turned on so as to remove air from space 21 and from within the tail pipe 11, the water therein before condenser operation taking the levels shown in Figure 2. Removal of atmospheric air from the tail pipe will prevent any surging action in barometric tail pipe 11, which would otherwise occur through the efforts of the volume of entrapped air in the pipe to escape through the bottom opening of the barometric pipe.

The predetermined degree of vacuum or absolute pressure to be carried in gas collecting space 21 is so arranged that the operating height 29 of the surface 50 of water in the outlet well 19 always will be safely below the water overflow level 20. Height 29 should in general be about two feet which represents the usual range in annual local variation of atmospheric barometric pressure. This will vary, of course, in accordance with local conditions. The water levels 30 and 20 indicated in Figure 2 are those before the condenser is started.

Taking the example previously mentioned of a maximum barometer pressure of 30.72 inches and minimum of 28.92 inches (equivalent to 15.10 pounds and 14.2 pounds, respectively) representing a variation of .9 pound per square inch absolute, if a degree of rarefaction of 14.05 pounds absolute (28.6 inches Bar.) is provided in space 21, the maximum height 29 will never exceed two feet five inches, and the overflow level 20 of the tube 19 can be set at a height of three feet above the hot well water level 30. By this arrangement it is assured that the level of the water in the catch basin 25 of chamber 18 in which the barometric pipe 11 is sealed will never vary irrespective of any barometric pressure change. There also is assured an unvarying depth and head of water column between the water level at 20 and the water level of the column 31 in the tail pipe 11, with the condenser in operation, this depth being indicated as 56 in Figure 1. The overflow level governed by the top 20 of tube 19 is entirely independent of the varying height of the water column 32 (top of operating surface indicated at 50) in the waste water conduit 19.

Depending upon the operating cycle of the steam condenser as regards load, the air and non-condensable gaseous content of the water column discharging through barometric pipe 11

will vary. In the cycle herein, the steam jet 22 removes such air and non-condensable gases for discharge to atmosphere and is prevented from exceeding the predetermined operating condition, or absolute pressure to be maintained, through the relief valve 26 being set to admit sufficient air to so accomplish. As the vacuum maintained by pump 22 in the gas collecting space 21 is low, the size of the vacuum pump is small and the power to operate it also small.

An alternative form is shown in Figures 4, 5 and 6, wherein the condenser is indicated at 33 and the tail pipe at 34. Chamber 35 has steam jet air pump 36 connected thereto with an air outlet 31. Partition 37 maintains level 38 within the closed chamber 35. The waste water outlet is down column 39 through opening 40 below the shell of chamber 35 to hot well 41. The water level 42 in hot well 41 is maintained by weir 43. Valve 44 is connected from gas collecting space 45 to tail pipe 46 through connection 47. This connection is usable in the starting of the condenser in the same manner as connection 28 and valve 27 of Figure 2. Vacuum relief valve 51, similar to valve 26 of Figure 2, may be provided. It is to be understood that various means of pressure control in the gas collecting chamber may be employed.

The operation of the device of Figures 4, 5 and 6 is similar to that of Figures 1, 2 and 3.

The water coming down tail pipe 46 has its direction reversed at the bottom of the pipe and again at the top of the catch basin 52 as said water flows over the top of the partition 37. In this manner, separation of the air and non-condensable gases is facilitated. The terms "air" and "gas" are used interchangeably.

It is to be understood that various changes and modifications may be made in the forms specifically illustrated without departing from the spirit of the invention or scope of the appended claims.

I claim:

1. In a condensing system of the character described, a barometric tail pipe adapted to be connected to a direct contact condenser, a closed chamber around the outlet of said tail pipe, a partition forming a catch basin inside said chamber, said tail pipe emptying into said catch basin, means to maintain an absolute pressure in said chamber between atmospheric and that of said condenser and remove gases from the top of said chamber, and an atmospheric seal tank surrounding the bottom of said chamber through which liquid is removed there being an outlet from said chamber into said seal tank.

2. In a condensing system including a direct contact condenser, a barometric tail pipe connected to said condenser, an atmospheric liquid seal tank into which said tail pipe discharges, a chamber connected to said seal tank and enclosing the tail pipe exit end, said chamber having a gas collecting space above the tail pipe exit end, the discharge point from said tail pipe into said seal tank being spaced at all times from the liquid level of said seal tank, gas removal apparatus connected to said gas collecting space, said gas removal apparatus maintaining substantially constant absolute pressure in said chamber between atmospheric and that to be maintained in said condenser whereby changes in atmospheric pressure do not substantially affect the condenser pressure.

3. A direct contact condensing system including a gravitational barometric tail pipe adapted to be connected to a direct contact condenser, a

closed chamber surrounding the outlet end of said tail pipe to receive liquid flowing from said outlet, an air removal means connected to the top of said chamber to separate air and gases from gravitationally flowing liquid in said tail pipe, and an atmospheric seal tank connected to the bottom of said chamber through which liquid is removed, the discharge point from said tail pipe into said seal tank being spaced at all times from the liquid level of said seal tank.

4. In a condensing system including a direct contact condenser, a barometric tail pipe adapted to be connected to a direct contact condenser, a closed chamber into which liquid from said tail pipe may flow, means to remove gases from the upper part of said chamber, said means connected to said chamber subjecting said chamber to an absolute pressure therein between atmospheric and that in said condenser, an atmospheric liquid seal tank connected to the bottom of said chamber, and a partition, said partition forming a catch basin in said chamber and having a height above the liquid level of said seal tank greater than the greatest variation in liquid level in said chamber due to atmospheric pressure variation whereby the pressure in the condenser is not substantially affected by variations in atmospheric pressure.

5. In a condensing system, closed chamber, a gravitational barometric tail pipe connected to a direct condenser and terminating near the bottom of said chamber, a vertical partition inside said chamber defining a catch basin into which said tail pipe empties, liquid from said tail pipe flowing upwardly over the top of said vertical partition, a discharge conduit connected to the side of said partition opposite to the tail pipe, said discharge conduit leading into an atmospheric seal tank, and a gas removal means connected to the top of said chamber.

6. In a device of the character described the combination of a barometric direct contact steam condenser, a gravitational barometric waste pipe connected thereto, encasement means surrounding the opening of said waste pipe, said encasement means having a gas collecting means at its top and a liquid seal waste pipe at its bottom, an atmospheric seal tank surrounding the bottom of said encasement, the discharge point from said barometric waste pipe into said liquid seal waste pipe being at all times spaced from liquid level in said liquid seal waste pipe, rarification means, and means to control said rarification means to provide a degree of rarification in said chamber to prevent flooding of the gas collection chamber.

7. A barometric type condensing system including a direct contact condenser, a barometric tail pipe connected to said condenser, a gas collecting chamber connected to the exhaust of said tail pipe, gas removal means connected to said chamber to maintain said chamber at a pressure between that in the condenser and atmospheric pressure, and a liquid removal means connected to said chamber sealing said gas collecting chamber from atmosphere, the discharge point of said tail pipe into said liquid removal means being spaced at all times from the liquid level of said removal means.

8. In a condensing system, an enclosed chamber, a gravitational liquid leg barometric tail pipe connected to a direct contact condenser and to said chamber to provide a change in direction of the liquid as the chamber is entered thereby, a discharge outlet from said chamber into an atmospheric liquid seal tank surrounding the bot-

tom of said chamber, the discharge point from said tall pipe into said seal tank being spaced at all times from the liquid level of said seal tank, and means at the top of said chamber to remove gases and subject the chamber to an absolute pressure between atmospheric and that of the condenser to which the tall pipe is connected.
